UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,982, dated July 1, 1890.

Application filed April 15, 1890. Serial No. 348,119. Term of patent 3½ years.

To all whom it may concern:

Be it known that I, HENRY O. SCHMIDT, a citizen of the United States, residing in New York, in the county and State of New York, 5 have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

15 A is the body part, and spreads as it extends upward, and is mounted by a curved cap B of plain surface. The lower part of the body A swells out, as at F, and immediately above this portion it is encircled by double annular bands C, plain. The body is ornamented by vertical bars G of plain sur-

face and H of ornamental work. The bars G 20 are flattened, so as to reflect the light. The lower part of the body is bounded by the annular band D of plain surface, and the lower apron E projecting downward therefrom.

The handle is made of any suitable material.

Having now described my new design, what I claim as new, and desire to secure by Letters Patent, is—

The design for cane or umbrella handles, 30 substantially as herein described and shown.

In testimony of which invention I have hereunto set my hand.

HENRY O. SCHMIDT.
